UNITED STATES PATENT OFFICE.

WILBUR B. DRIVER, OF EAST ORANGE, NEW JERSEY, ASSIGNOR TO NEW YORK BATH MANUFACTURING CO., A CORPORATION OF NEW YORK.

INFANT'S DRESSING STAND.

1,426,160.

Specification of Letters Patent. Patented Aug. 15, 1922.

Application filed March 11, 1920. Serial No. 364,908.

To all whom it may concern:

Be it known that I, WILBUR B. DRIVER, a citizen of the United States, residing at East Orange, county of Essex, and State of New Jersey, have invented certain new and useful Improvements in Infants' Dressing Stands, fully described and represented in the following specification and the accompanying drawings, forming a part of the same.

This invention relates to certain improvements in dressing stands for infants.

It is the especial object of the present invention to produce a stand on which an infant may be dried after its bath or otherwise cared for, thus avoiding the necessity of holding the infant in the lap and permitting it to be better and more easily handled, this stand being provided with means for preventing the infant from accidentally rolling off the stand.

A further object of the invention is to provide a stand which shall be light, which can be folded up so as to be readily transportable and stored in a small space, and which may be provided with a protecting apron having pockets or receptacles for carrying toilet articles.

With these and other objects not specifically referred to, in view, the invention consists in certain novel constructions and parts which will be fully described in connection with the accompanying drawings and then specifically pointed out in the claims hereunto appended.

In these drawings:

Figure 1 is a perspective view of the improved stand in its preferred form.

Figure 2 is a central vertical section 40 through the stand shown in Fig. 1.

Figure 3 is a detail sectional view on an enlarged scale showing the method of attaching the fabric to the stand.

Referring now to the drawings, the stand in its preferred form will be a folding stand, that is, a stand which may be collapsed so that it can be readily carried about and can be kept, when not in use, in a small space, which is an item of importance in bath room furniture.

In the construction shown, there is provided a pair of oppositely disposed legs 1, pivotally secured at 2, to a similar pair of oppositely disposed legs 3. The legs 1 are connected together by a tie rod 4, and the

legs 3 are connected by a similar tie rod 5. These parts may conveniently be made of wood, or any light metal may be employed. These pairs of legs are movable on pivots 2, to open and closed position, and in the best form of stands means will be provided for holding the legs in open position, as shown in Fig. 1. While this means may be varied, as there shown, there is provided at each end of the stand latches 6, being pivoted at 7 to one of the legs and having hooked ends 8 adapted to take over pins 9 on the other legs. With this construction the parts may be readily collapsed or held firmly locked in open position.

Secured to the upper ends of the legs are transverse supporting bars 10, 11, which form supports for the flexible fabric as canvas 12, which when the parts are in open position extends between the supports and on which the infant rests. This fabric is secured at one end to one of the supports, as 10, in any suitable manner, as by means of tacks 13. The fabric is extended across between the supports and is secured to the support 11, in any suitable manner, as by tacks 14.

In accordance with the invention, the stand is formed to provide low walls or ridges which will act to prevent the infant from accidentally rolling off the stand sideways. While this may be accomplished in various ways, a simple and convenient way is that illustrated in which the fabric is depressed between the supporting bars. This is done by providing what may be termed stretcher bars 15, one of these bars being provided at each side of the frame, being secured in the legs and located a sufficient distance below the supporting bars 10, 11 to form ridges or walls 16, of the desired depth. The fabric 12 is looped around under the stretcher bars as shown in Figs. 2 and 3, and if desired may be caught by stitches 17 or other suitable fastening devices for holding it firmly in place around the stretcher bars.

With this construction a firm support for the infant is provided and one which tends to prevent the infant from accidentally falling off the support.

In constructions embodying the invention in its best form, an apron will be provided for protecting the person attending the infant from being wet. While this apron

may be formed in various ways, preferably the fabric 12 is extended at one side beyond the supporting bars, as beyond bar 11, to form the apron, marked 18, and further-
5 more in the best constructions, this exten-
sion is cut away centrally, as indicated at 19, to provide room for the knees of a sit-
ting person. If desired large pockets 20
may be formed on each side of the apron and
10 additional middle pockets 21 may likewise
be formed in the apron, these pockets forming convenient means for holding small
toilet articles or articles of wearing ap-
parel.

15. It will be seen by the construction shown
and described, that a very convenient dress-
ing stand has been provided, in which there
is a comfortable support for the infant, so
formed as to prevent the infant from acci-
20 dentally falling off the stand, and at the
same time a protection for the person at-
tending the infant.

While the invention has been shown and
described in its preferred form, it will be
25 understood that various changes may be
made in the means for producing the walls
or ridges and in the means for securing the
fabric to the supporting bars, without de-
parting from the invention.

30. What I claim is:

1. A dressing stand for infants, comprising
a frame including opposed pairs of piv-
otally connected legs and oppositely dis-
posed supporting bars secured lengthwise
35 to the upper portions of the opposed legs, a
fabric top secured to the supporting bars and
extending therebetween and stretcher rods
at each side of the frame upon which the

fabric is stretched, said rods being located
below the supporting bars and acting to de-
40 press the fabric slightly between the bars
and thus form low sidewise extending ridges
or walls, as and for the purpose described.

2. A dressing stand for infants, comprising
a folding frame including opposed pairs
of pivotally connected legs and supporting
bars secured to the upper ends of the legs,
and a fabric top secured to the bars and ex-
tending between them and extended at one
side so as to depend below the bar at that
50 side and form a protecting apron, a latch
bar pivoted to one leg and adapted for re-
movable engagement with the other leg to
releasably hold the frame in an extended
position, and stretcher rods located below
55 the supports around which the fabric is
passed and acting to slightly depress the
fabric between the bars and form low ridges
or walls, as and for the purpose described.

3. A dressing stand for infants, comprising
a folding frame including opposed pairs
of pivotally connected legs, a latch associ-
ated with each pair of legs for releasably
holding the same extended, opposed sup-
porting bars connected to the upper portions
65 of the opposite legs, stretcher rods located
slightly below the supporting bars and con-
nected with the opposite legs and a fabric
top secured to the bars and about the rods
so that the rods will hold the apron rela-
70 tively taut and provide opposed ledges sub-
stantially as described and for the purposes
set forth.

In testimony whereof, I have hereunto
set my hand.

WILBUR B. DRIVER.
